Primary Examiner — Katrina N Gonzalez(74) *Attorney, Agent, or Firm* — Merchant & Gould P.C.(57) **CLAIM**

The ornamental design for a grooming hair accumulator for animal, as shown and described.

DESCRIPTION

FIG. 1 is a top perspective view of the new design;
 FIG. 2 is a bottom perspective view of the new design;
 FIG. 3 is a top view of the new design;
 FIG. 4 is a bottom view of the new design;
 FIG. 5 is a right side view of the new design, the left side view being a mirror image thereof;
 FIG. 6 is another perspective view, but shown with the handle and head separated for completeness of illustration;
 FIG. 7 is another perspective view, but shown with the handle removed for completeness of illustration;
 FIG. 8 is another perspective view thereof; and,
 FIG. 9 is another perspective view thereof.
 The broken lines illustrate portions of the grooming hair accumulator for animal that forms no part of the claimed design.
